FOOT FOR CHAIR LEGS.

Otto H. Kistemacher, Oklahoma City, Okla.

Application November 23, 1935, Serial No. 51,195.

3 Claims. (Cl. 155—77)

My invention relates to an attachable foot for the bottoms of chair legs, and particularly for use on chairs which are likely to be tilted during the use of the chairs.

The objects of my invention are to provide a device of this class which is new, novel, practical and of utility; which may be manufactured at the time of the manufacture of the chair; which may be manufactured as a separate attachment adapted to be attached to a chair after its manufacture; which is simple; which is compact; which can be quickly and easily attached and installed; which is comparatively cheap in manufacture; which will prevent the free ends of the legs of a chair from injuring and defacing the floor; carpet, linoleum, or other floor covering; which will permit the easy tilting and positioning of a chair for comfort without injury to the floor or floor coverings; which will prevent the frequent breaking off of the rear legs of a chair by tilting, and their adhering to the linoleum or other floor covering; which will furnish a greater and a curved seating surface for contacting the floor or floor covering; which will furnish many differently angled seating surfaces for the rear legs of a chair thereby resting the occupant of such chairs during long occupation of the chair at one sitting; and, which will be efficient in accomplishing all the purposes for which it is intended.

The free ends of the legs of a chair, and particularly the two rear ones, as they are at the present time ordinarily made, are comparatively small and although usually round, have nevertheless sharp angles. During the period of time during which they are ordinarily used this might be of no marked disadvantage. But during long sessions, or periods of use in the same chair, such as during usual card games, dominoes and the like, and around waiting rooms in offices, depots and the like, the occupants become tired and are apt to change their positions, and to tilt the chairs. During such use the linoleum and other coverings become cut and partially perforated, from contact with the chair legs.

In a short time the general surfaces of such coverings become so cut up as to require new floor coverings, and before such replacement is made, present anything but a smooth surface.

The use of my device obviates all of the disadvantages above enumerated, and in addition furnish much comfort to the occupant by giving him many positions in which to use the chair in comfort.

With these and other objects in view as will

more fully appear hereinbelow, my invention consists in the construction, novel features, and combination of parts hereinafter more fully described, pointed out in the claims hereto appended, and illustrated in the accompanying one-sheet drawing, of which,

Figure 1 is a perspective view showing a table, and an occupant of a chair in a tilted position with two of the devices installed on the free ends of the rear legs of the chair and the free ends of the front legs raised off of the floor; and,

Figure 2 is a perspective view of the device showing the opening for the installation of the free end of one of the legs.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawing is to be interpreted as being illustrative and not restrictive.

The inventive idea involved is capable of receiving a variety of mechanical expressions one of which, for the purpose of illustrating the invention, is shown in the accompanying drawing 30 wherein:—

The numeral 1 shown in Fig. 1 designates a portion of a table at which a man 2 is seated in a tilted position on a chair 3 playing a game of dominoes 4; the position of the man's body 35 and especially his feet 5 indicate one position assumed while the chair is tilted; numerals 6 and 7 indicate as a whole two of the devices installed on the free ends of the two rear legs 21 and 22 of the chair, and the relative position of such 40 devices on the floor or floor covering while the chair is tilted in that position. It will be observed that many other tilted positions will be permitted by the curved lower surface 15 of said devices as shown by numerals 6 and 7. 45

It is deemed sufficient to describe one of the devices as they are practically identical, though they are used in pairs. The device, one of which has already been hereinbefore referred to by the numeral 7, has preferably a flat top surface 8; a front end 9 having a semi-cylindrical surface 10; a rear end 11 also having a semi-cylindrical surface 12; right and left surfaces 13 and 14, respectively, the surface 13 being clearly in view; 50 55

COMBINED WRAPPING AND SLICING MACHINE

Carl Littlefield, Battle Creek, Mich., assignor to
Battle Creek Bread Wrapping Machine Company, Battle Creek, Mich.

Application March 2, 1934, Serial No. 713,677

64 Claims. (Cl. 93—2)

The main objects of this invention are:

First, to provide a combined wrapping and slicing machine which may be readily adapted for use as a machine for slicing and wrapping 5 sliced loaves of bread or for the wrapping of unsliced loaves of bread.

Second, to provide an improved conveyor means for the handling of sliced loaves of bread.

Third, to provide an improved means for sealing 10 wrapped articles, particularly irregular articles such as loaves of bread.

Fourth, to provide improved means for sealing the ends of wrapped articles which is highly efficient and does not tend to distort or displace 15 the wrapper as it is conveyed through the sealing station.

Fifth, to provide an improved wrapping and conveying means.

Sixth, to provide an improved means for 20 transferring sliced loaves and controlling the feeding of loaves to the slicing mechanism.

Objects pertaining to details and economies of 25 my invention will definitely appear from the description to follow. The invention is defined in the claims.

A machine which embodies the features of my invention is clearly illustrated in the accompanying drawings, in which:

Fig. 1 is a side elevation of the wrapping and 30 slicing portion of the machine looking from the right of Fig. 2.

Fig. 2 is a side elevation of the feed portion of 35 the machine for conveying the articles to be sliced and/or wrapped into the machine and also delivering the wrapped articles, this view being complementary to Fig. 1.

Fig. 3 is a perspective view of my improved 40 slicing and wrapping machine with the slicing unit in inoperative position, a portion of the conveyor for the work into the machine and for its delivery from the machine being broken away.

Fig. 4 is a detail vertical longitudinal section 45 through the paper feed and wrapping and sealing portion of the machine.

Fig. 5 is an enlarged fragmentary plan view of 50 the sealing mechanism partially in horizontal section on line 5—5 of Fig. 6.

Fig. 6 is a vertical transverse section on a line 55 corresponding to line 6—6 of Figs. 5 and 7.

Fig. 7 is an enlarged fragmentary longitudinal section corresponding to that of Fig. 4 showing details of the sealing mechanism taken on line 7—7 of Fig. 5.

Fig. 8 is an enlarged fragmentary section

showing details of the bottom sealing means in operative relation to a wrapped loaf.

Fig. 9 is a fragmentary view partially in section on line 9—9 of Fig. 10 showing details of the loaf feed and feed control mechanism. 5

Fig. 10 is a fragmentary plan view of the parts shown in Fig. 9.

Fig. 11 is an enlarged fragmentary view partially in section on line 11—11 of Figs. 10 and 12.

Fig. 12 is a fragmentary view partially in 10 transverse section on line 12—12 of Fig. 11, the view being taken with the feed members in advanced position as shown by dotted lines in Fig. 9.

Fig. 13 is a fragmentary view partially in section on a line corresponding to line 13—13 of 15 Fig. 12.

Fig. 14 is a fragmentary view partially in section on line 14—14 of Fig. 15 showing details of the driving and timing means.

Fig. 14—A is a fragmentary view complementary to Fig. 14. 20

Fig. 15 is an enlarged fragmentary view mainly in section on line 15—15 of Fig. 14 showing details of the gearing.

Fig. 16 is a fragmentary perspective view 25 showing details of the wrapping mechanism.

Fig. 17 is a fragmentary view of a modified form of sealing means.

Fig. 18 is a fragmentary view of the sealing means of Fig. 17 taken on line 18—18 of that 30 figure.

The machine illustrated in the accompanying drawings is a highly practical embodiment of a machine adapted for the slicing and wrapping of loaves of bread or for the wrapping of unsliced 35 loaves. While certain features are especially designed for embodiment in such a machine, others are highly desirable for use without the combination feature and for wrapping articles other than bread. 40

The main frame 1 of the machine is of suitable form and dimensions to support various operating parts and is provided with a forwardly projecting top portion 2 which overhangs a part of the adjustable frame 3. The base 4 for the 45 main frame 1 is provided with a lateral extension 5, this lateral extension and the main frame having tracks or ways 6 thereon disposed transversely of the machine and on which the slicing machine designated generally by the numeral 7 is 50 mounted.

The slicing machine is provided with rollers or carrying wheels 8 traveling on the track or way 6 so that the slicing machine may be moved into operative position and the bread passing into the 55

machine is delivered thereto. The slicing machine is shown in operative position in Fig. 1 and in inoperative position in Fig. 3.

The adjustable frame 3 is slidably supported at its inner end on the pedestals 9 and at its forward or outer end on the pedestals or uprights 10 which have slide bearings 11 coacting with the slides 12 on the frame. The frame has slides 13 coacting with the slide bearings 14 on the pedestals 9.

The overhanging top portion 2 of the main frame is supported by the side rails or extensions 15 mounted on the upper ends of the pedestals 10, see Fig. 2. The adjustable frame is mounted for adjustment so that when in one position the slicing machine unit may be adjusted to operative position, and, when the slicing machine unit is withdrawn or in inoperative position as shown in Fig. 2, this frame may be adjusted to its inner position into cooperation with other parts of the feeding mechanism.

In this description I have treated the portion of the machine shown in Fig. 2 as the front end of the machine, inasmuch as the loaves or articles to be wrapped are fed into the machine from that end. It will be understood, however, that the articles are also discharged in wrapped condition from the same end of the machine. The unwrapped articles are designated by the numeral 16 while the wrapped articles are designated by the numeral 17.

I will first describe the path of the articles through the machine and then describe the several mechanisms in detail.

The loaves of bread or other articles to be wrapped or operated upon are placed by hand or delivered automatically upon a feed conveyor mechanism designated generally by the letter A. This feed conveyor A delivers to the slicing table 18 (Fig. 3) of the slicer 7 when the slicer is in operative position or to the reciprocating transfer conveyor mechanism designated generally by the letter B, see Fig. 11. This transfer conveyor mechanism B delivers the loaves or articles to be wrapped to a conveyor designated by the letter C, see Figs. 4 and 11, by which conveyor the loaves are delivered to the elevator D, Fig. 4. This mechanism delivers the loaves to the wrapping mechanism designated generally by the letter E, Fig. 4, from which they are delivered to the sealing mechanism designated generally by the letter F, Fig. 4. The sealing mechanism delivers the articles to the delivery conveyor designated generally by the letter G, see Figs. 2 and 3.

The feed conveyor mechanism comprises a feed table 19 on which the loaves may be placed, a side or positioning bar 20 being arranged at the rear of this table. The bottom conveyor belt 22 is supported at its forward or outer end by the pulley 23 and at its inner end by the pulley 24. This bottom conveyor belt 22 transfers the loaves from the feed table 19 between the side conveyor belts 25 which engage the ends of the loaf and it is carried forward quite positively by the friction of these belts. When the slicing machine is in operative position the loaves are fed across the slicing table and into the knives of the slicing machine by the pressure of succeeding loaves. This slicing machine unit is not described and illustrated in detail as it preferably embodies the features of my application for Letters Patent Serial No. 396,033, filed September 30, 1929.

The belts 25 are provided with suitable pulleys at their ends, the belts and their pulleys and the carrying frames therefor comprising side bars

26 and brackets 27 mounted on reversely threaded screws 28 connected by suitable sprocket chains and suitable coacting sprockets 29. The sprocket chains are driven from a hand wheel 30 so that the side belts are simultaneously adjusted to and from each other to accommodate loaves of varying lengths. A belt tighter unit designated generally by the numeral 31 is provided for each feed conveyor side belt.

The pulley 23 is driven from the shaft 32, and the shaft 33 is connected to the shaft 32 by a variable speed transmission gearing designated generally by the numeral 34, see Fig. 2. The shaft 33 is provided with universal joints 35. The shaft 33 is connected to the pulley through a suitable gearing, the gear box 36 of which is shown in Fig. 2. The pulleys 37 of the side conveyor belts are the driven pulleys and these pulleys are mounted on the vertical shafts 38.

The shafts 38 have beveled gears 39 on their upper ends meshing with the gears 40 on the transverse shaft 41. This transverse shaft is connected by the sprocket chain 42 and suitable sprockets to a beveled gear 43 which meshes with a beveled gear 44 on the end of the shaft 33 which projects from the variable speed transmission gear box. This feed mechanism, when operatively associated with the slicing machine, is substantially that of my application for Letters Patent Serial No. 654,481, filed January 31, 1933.

As stated, the feed conveyor may be adjusted to cooperate with the slicing machine or with certain of the conveyor features when the slicing mechanism is in inoperative position. This adjustment is effected by means of the screw 45 coacting with a nut 46 on the pedestal 9 and connected to the depending bracket 47 on the frame 3. The screw is provided with a hand-wheel 48, Fig. 2.

The slicing machine has a guide bar 49 on the top thereof coacting with a guide bar 50 on the frame 3. When the frame 3 is retracted the slicing machine may be pushed into operative position and locked in that position by means of the screws 51 which engage the guide bar 49. With the slicing machine in operative position the loaves are delivered from the slicing machine on to the delivery table 52. When the slicer is in inoperative position the loaves are driven directly by the feed conveyor to this delivery table 52.

The loaves, either sliced or whole as the case may be, are delivered from this table 52 to the conveyor slideway 53 of the conveyor C by means of transfer jaws 54 engaging the ends of the loaf at the position shown by full lines in Figs. 9 and 11, carrying the loaf forwardly on to the conveyor slideway 53. These jaws 54 are carried by arms 55 pivoted at 56 on the reciprocating carriage 57 which is mounted on the slideway 53 disposed centrally above the path of the loaves. This carriage includes a crosspiece 59.

The carriage is reciprocated by means of the arms 60 on the rockshaft 61, the arms being connected to the cross piece 59 on the carriage by means of the links 62. The jaw arms are pivotally mounted on the outer ends of the jaw supporting bars 63 which are slidably mounted on the carriage for longitudinal adjustment. These bars are provided with racks 64 coacting with a pinion 65 having a shaft 66 provided with a handpiece 67 by means of which the jaw supporting bars may be adjusted to adjust the jaws to the length of the particular article to be wrapped.

The opening and closing of the jaws is controlled by the reciprocation of the carriage. The closing of the jaws is timed by the article that is advanced either from the feed conveyor or through the slicer to position to be engaged by the jaws, a loaf of bread being indicated at 16, Fig. 9.

A trip 68 projects through a slot in the table 52. This trip is mounted on a rockshaft 69 having an arm 70 thereon connected by the link 71 to a latch lever 72 pivoted at 73. This latch lever coacts with the trip lever 74 pivoted at 75 and actuated by means of the spring 76. The latch lever and the trip lever have coacting engaging parts as shown in Figs. 9 and 14, the parts being shown in engagement in Fig. 14 and in disengaged position in Fig. 9. A weighted arm 77 on the rockshaft 69, see Fig. 14, returns the trip and connected parts to initial position.

The trip lever 74 is connected by a link 78 to an arm 79 on the rockshaft 80. Each jaw supporting bar 83 is provided with a head or bracket 81 at its outer end and carrying the pivot 56 for the jaw arm and also slidably supporting a jaw controlling cam member 82 having a cam recess 83 therein into which the roller 84 on the arm drops under the action of the spring 85, thereby opening the jaws. The flat side of the cam member coacts with the roller to close the jaws. At the end of each forward stroke of the carriage the cam member engages the bumper 86, see Fig. 9, and on the return stroke of the carriage engages with the actuating tappet 87 providing that that tappet is in its actuated position.

The tappets 87 are mounted on a rockshaft 88 provided with a weighted arm 89 acting to swing the tappets to inoperative position. The tappet is shown in operative position in Fig. 9 and in inoperative position in Fig. 11. The tappet 40 is controlled through the trip lever mechanism described, the rockshaft having arms 90 projecting forwardly therefrom to be engaged by the spring extensions 91 on the arms 92 carried by the rockshaft 80.

Referring to Fig. 9, it should be pointed out that the tappet is shown in actuated position by full lines and in normal or initial position by dotted lines, while the lever 92 is shown in its unactuated position, being held in this position 50 by the detent 93 on the rockshaft 94. The detent 93 is tripped by the resetting dog 95 which is pivoted at 96 on the head 81. This resetting dog is controlled by the cam member 82 which has a recess 97 into which the roller 98 on the resetting dog drops when the cam member is actuated by coming into contact with the abutment 86, see the dotted position at the right of Fig. 9.

The resetting dog on the forward stroke of the carriage comes into contact with the trip arm 99 on the rockshaft 94, swinging the detent 93 out of engagement or into coacting relation with the lever 79, allowing the lever to move upwardly to the dotted position under the action of the spring 76 and swinging the arm 92 downwardly to actuate the tappet to cam actuating position. The actuation of the cam member 82 by the tappet to close the jaws also lifts the resetting dog 95, which is designed to engage an arm 100 on the rockshaft 80, resetting or forcing the arm 79 downwardly to be re-engaged by the detent 93.

The driving shaft 32 for the feed conveyor is also controlled through this article controlled trip mechanism. The rockshaft 76 has an arm

101 connected by the link 102 to the arm 103 controlling the pawl 104. This pawl coacts with a ratchet wheel 105 on the shaft 106 to control the rotation of the shaft; that is, when the pawl is in engagement the shaft is held against rotation, thereby holding the planetary control pinion 107 against rotation. This planetary control pinion engages a peripheral gear on the planetary drum 109 carrying the planetary gears 110. These planetary gears coact with a gear 111 keyed to 10 the shaft 112 and with the gear 113 rotatable on the shaft but pinned to the driven gear 114 meshing with the gear 115 on the shaft 32. It will be noted that this shaft is provided with a universal joint 116.

With this arrangement of the parts the feed conveyor is driven continuously through the mechanism described so long as the pawl 104 remains in engagement through the connections described, preventing the rotation of the planetary 20 drum. However, when the pawl is disengaged, the planetary drum is free to rotate and this results in the stopping of the gear 113 of the planetary gearing and consequently the feed conveyor. This control, as has been pointed out, is from the 25 trip 68 so that the feed conveyor is synchronized, either to feed the loaves to the slicing unit or directly to the table 52 in proper timed relation to be engaged by the jaws 54. These feed or transfer jaws 54 deliver to the conveyor way 53 30 of the conveyor C in timed relation so that the articles are picked up by the flights 117 on the conveyor chain 118. The transfer jaws gripping the ends of the loaf deliver it between the side bars 119 of the conveyor C between which it is 35 carried along by the flights and delivered on to the feed plunger or elevator 120 by which the loaves are delivered to the wrapping mechanism E. A stop plate 121 is provided to position the articles on the elevator, the elevator having 40 hold-ers 122.

As the article to be wrapped is lifted by the elevator it is carried against the under side of the wrapper and delivered with the wrapper to the wrapping mechanism E. The wrapper, indicated 45 at 123, is fed from the end of the machine, the roll being shown at 124. Feed rollers 125 and 126 deliver the paper to the cutter, the roller 125 being a friction roller and the roller 126 being preferably tubular to receive a chilling fluid, the 50 connection being shown at 127, Fig. 1, so that the waxed paper may be cooled or chilled where the machine is operating in such temperature as would soften the wax or paraffin. This prevents the machine from becoming clogged or gummed 55 by the wax. The cutter 128 is of the rotary type.

The paper is delivered from the feed rolls to the wrapper conveyor belt 129 and by it projected or fed on to the reciprocating table 130. This wrapper supporting table is designed when in its 60 actuated or forward position to receive the wrapper from the conveyor belt and effectively support it, preventing its sagging into the space above the elevator. The wrapper supporting table or slide reciprocates in the slideways 131 and is operated 65 from a lever 132 pivoted at 133 and connected by the link 134 to the arm 135 on the rockshaft 136 which is actuated from the arm 137 coacting with a suitable cam, not shown. This rockshaft carries an arm 138 connected to the slide bar 139 of 70 the elevator. This bar-like slide of the elevator reciprocates in guides 140 carried by cross rods 141 on the frame.

With this arrangement of parts the elevator and this paper receiving table or slide are actu- 75

ated in timed relation as the supporting slide must be withdrawn to permit the elevator to deliver the article to be wrapped to the wrapping mechanism.

- 5 To position the paper as it is delivered from the paper feed belt I provide a stop 142 carried by the cross bar 143, this cross bar being mounted on slides 144 provided with a rack 145 coating with pinions 146. These pinions are provided 10 with a handwheel 147. This provides means for rapid adjustment of the stop to properly position the wrapper and prevent overthrow thereof. The paper is held against the feed belt 129 to insure effective frictional engagement by means of the 15 roller 148 carried by the pivoted arm 149. The arm 149 of this friction roller is carried by the adjustable hanger 150 provided with a pivot 151 having an adjusting arm 152 thereon operatively associated with an indicia segment 153.
- 20 By manipulation of this adjusting arm 152 the arm 150 may be swung, thereby positioning the roller 148 relative to the feed belt and determining the point at which the frictional engagement of the paper with the feed belt terminates, stopping 25 the feed of the paper.

The loaf or article to be wrapped is delivered by the article feed conveyor or elevator between the pusher 154 and the holder jaw 155 opposed thereto, see Fig. 4. The pusher is adjustably 30 mounted on the carriage designated generally by the numeral 156. A clamping means 157 is provided for securing the pusher to this carriage. The opposed holding jaw 155 is pivoted at 158 on the frame and is adapted to be swung upwardly 35 out of the way of the article as it is carried forward by the wrapper carriage.

The bottom flap folder is indicated at 159, the front end flap folders at 160, the top end flap folder at 161 and the front end flap folders at 40 162. These folders form no part of my present invention and are not described with further detail. It will be understood, however, that the bottom folder 159 is actuated in proper relation to the movement of the feed plunger so that it serves 45 as a support for the article when the plunger is retracted.

The gripper 155 is actuated in timed relation to the movement of the carriage so that it is 50 swung upwardly out of the path of the article to be wrapped but keeps a holding engagement with the front side thereof until the front portion of the wrapper is engaged by the front edge of the sealing way 163.

From the final end flap folders 162 the article is 55 delivered between the end sealers which, in the preferred embodiment of my invention, comprise a plurality of sealing bars 165 disposed in parallel relation and mounted on double eccentrics 166 and 167, see Figs. 5 and 6. It will be noted that 60 alternating bars are mounted on the eccentric straps 168. The eccentrics are carried by vertical spindles 170 having parts 171 at their lower ends slidably mounted on the shaft 172 and the cross rod 173 on the frame so that the sealer units 65 may be adjusted to and from each other. The spindles are connected at their upper ends by the 70 housings or guards 173 mounted upon the reduced upper ends of the spindles and secured thereto by the nuts 174.

75 The eccentrics 166 have sleeve-like extensions 175 at their lower ends provided with beveled gears 176 meshing with the gear 177 on the shaft 172. The double eccentrics are so disposed that one set of sealer bars is advanced into loaf-engaging position when the other is retracted. The

sealer bars are given an orbital movement, that of the sets of bars alternating so that the loaf or article being sealed is constantly engaged by sealer bars and moved forwardly owing to this alternate engagement of the sets of bars, the forward motion being substantially continuous.

With this arrangement there is no sliding engagement of the wrapper with the sealers, the motion of the sealer bars being such that a substantial period of contact is maintained but 10 without wiping or sliding engagement. The sealer bars are electrically heated by heating elements designated generally by the numeral 179.

The bottom seal is effected in a similar manner, that is, the finger-like bottom sealers 180 15 are pivotally or rockingly mounted on the rod 181 carried by the arms 182 on the cross rod 183. This cross rod is mounted on the carriers 184 slotted at 185 to engage the support 186 and supported at the other end by the eccentrics 187 fixed 20 to the shaft 172 and engaging a suitable bearing 188 on the supports, see Fig. 5. The sealer members 180 are independently pivoted on the rod 181 and are urged yieldingly upward by means of the springs 189 secured at one end to the pin 191 on 25 the stop arm 192 and at the other end to pins 193 provided therefor on the rod 183. The stop arm is adapted to coact with the cross rod 183 to limit the upward movement of these sealer members. The shaft 181 is a tubular shaft, the heating element 181' being arranged therein as shown 30 in Figs. 5 and 8.

With this arrangement the sealing fingers 180 are given an orbital motion, their forward movement taking place while they are at the upper reach of their stroke, so they travel with the article being sealed. The sealing fingers yield so 35 that they conform to an irregular or yielding surface, such as a loaf of bread, and supply sufficient pressure to maintain contact for such period 40 as will insure effective sealing.

During its passage through the sealing mechanism the bread or other article being wrapped is urged downwardly by means of the pressure bars 194 which are pivoted at 195 on the hanger 45 arms 196, which are in turn pivoted at 197 on the housings 173. The adjustable rests 198 in the form of screws are threaded through suitable bosses or enlargements 199 on these arms, the screws resting on the top of the housings. This 50 limits the downward movement of the pressure bars so that the article can be wrapped and later 55 pass under the forward ends of the bars which are preferably upturned as indicated in Fig. 5.

The housings 173 serve as guards for the sprocket chains 200 which coact with the sprocket wheels 201 which are secured to the eccentrics 166 and 167.

By this arrangement the sealing both at the ends and bottom is effected by means which, in effect, travel with the article being sealed so that there is no tendency for displacement of the folds for the wrapper or to displace the wrapper on the wrapped article.

These sealing elements deliver the wrapped 65 sealed article to the delivery conveyor G, which comprises the slideway 202 and side conveyor belts 203 and 204, there being a pair of these side conveyor belts at each side of the way. These side conveyor belts are continuously driven, 70 and the pulleys 205 mounted on vertical shafts 206 have gears 207 at their lower ends meshing with gears 208 on the shaft 209. This shaft 209 is connected by the sprocket chain 210 and suitable sprockets to the shaft 172 through which 75

the feed conveyor belt is driven by the mechanism previously described.

The delivery conveyor belts 203 and 204 are provided with suitable belt tighteners designated 5 generally by the numeral 211, see Fig. 2, the purpose of this being to secure the desired tension to engage the upper and lower portions of a wrapped loaf of bread, the upper portion of which may be bulged or enlarged relative to the lower 10 portion.

The pulleys at the outer ends of the belts 203 and 204 are driven through the shafts 212 connected to the upper ends of the shafts 206 through suitable gearing, designated generally 15 by the numeral 213, housed within a gear box as illustrated. The shafts 212 are connected to the shafts 214 for these outer pulleys through gearing designated generally by the numeral 215. This arrangement permits the inner reaches of 20 the belts to be kept taut and in supporting driving engagement with the ends of the sealed articles.

The delivery conveyor serves also as a cooling conveyor, that is, the sealed flaps are held in 25 sealed position until sufficient time has elapsed for the complete setting of the wax.

The side conveyor belts, or, rather, their supports 216, are adjustably mounted on the cross rods 217 for adjustment by means of the right 30 and left hand screw 218 which has suitable gear connections to the shaft 219 geared to the shaft 186 of the handwheel 221. The shaft 186 is connected by the sprocket chain 222 to the adjusting screw 223 for the folders 160 and 161 and 35 the grippers 155, and to the screw shaft 224 for the brackets or supports carrying the side bars 119 of the conveyor C.

The rear flap folders 162 are mounted on forwardly projecting bracket-like arms on the housing members 173 to be adjusted with the side sealers. This adjustment is effected through 40 the shaft 186.

The forward ends of the side bars 119 are carried by the hangers 225 which are bracket 45 tensions on the side sealer supports. The shaft 186 performs the double function of slidably supporting the ends of the carrier 184, see Fig. 7, and has an adjusting screw, portions only of the shaft being threaded.

50 Through this arrangement of parts the mechanism is adjusted for different lengths of loaves through three adjustments, the feed conveyor through the handwheel 30, the transfer jaws through the adjusting member 67 and the parts 55 just described through the handwheel 221.

To accommodate loaves of different widths the abutment plate 121 is adjusted, this plate being carried by a sliding bracket 226 mounted on the slide 227 and provided with an adjusting lever 60 228 pivoted at 229 and having a slotted segment 230 and coating locking screw 231. The supporting slide for the abutment 121 is provided with a pointer 232 coating with a gage 233.

The feeding of the paper is controlled from 65 the trip 234 pivoted at 235 and provided with a return counterweight 236, see Fig. 1. This trip is connected by the link 237 to the clutch mechanism 238. The clutch mechanism drives the paper feed rolls through the shaft 239 which is 70 connected by the chain 240 and suitable sprockets to the shaft 241 of the lower cutter roll 242, which coacts with the cutter roll 128. These cutter rolls are connected by the gears 243 and 244, while the feed rolls 125 and 126 are connected 75 to the cutter roll 128 by a suitable variable speed

gearing designated generally by the numeral 245. The purpose of this variable speed gearing is to vary the speed of the feed rolls and thereby vary the size of the wrapper.

The driving pulley or roller 246 for the paper feed belt 129, which is preferably a plurality of belts in the form of coiled springs, is connected to the gear 243 by means of the gear 247. The paper feed belt is thus driven only through the wrapper feed control clutch, the object being to 10 stop the paper feed belts when the paper feed is stopped and thus prevent the wear on the wrapper or the distortion of the wrapper which would result from continuous driving of the paper feed belts with the paper feed rollers at rest. 15

It will be noted by reference to Fig. 16 that the bottom flap folder 159 is the full width of the wrapper and that the first bottom fold is folded or wrapped over the plunger 120, the movement of which is timed so that the wrapper is drawn 20 around the edge thereof as shown in Fig. 16. This acts to maintain the wrapper smooth throughout the width thereof and secures a highly desirable fold and close wrapping, which is of advantage 25 particularly in sliced loaves of bread where close wrapping serves to maintain the shape of the loaf, notwithstanding its sliced condition.

In the embodiment of my invention shown in 30 Figs. 17 and 18 the sealer members 248 are in the form of rollers or disks disposed in interlapping relation so as to present a fairly continuous forwardly moving surface to the article to be sealed. The shafts 249 of these rollers are provided with pinions 250 meshing with the worm gears 251 on the driving shafts 252 so that the 35 sealer members are all driven in the same direction and at uniform speeds. This results in translating the articles to be sealed through the sealing mechanism without wiping contact, as has been the practice heretofore so far as I am 40 aware, which results in more or less distortion and displacement of the wrapper and considerable irregularity in sealing.

With my sealing mechanism the heated sealer 45 elements travel with the article when in engagement therewith and serve as driving elements. This results in a very effective and uniform sealing of a plurality of superimposed or overlapped flaps and, as stated, without distortion or displacement thereof. 50

My combined slicing, wrapping and sealing machine is highly efficient and may be quickly 55 adjusted for the combined functions of slicing, wrapping and sealing, or for wrapping and sealing, thus adapting the machine for use in bakeries where bread is sold in both forms, which is in fact the common practice.

I have not attempted to illustrate or describe 60 various modifications and adaptations of my invention as it is believed that this disclosure will enable those skilled in the art to embody or adapt the same as may be desired.

Having thus described my invention what I 65 claim as new and desire to secure by Letters Patent is:

1. In a combined wrapping and slicing machine, the combination with a main frame, of an auxiliary frame mounted for adjustment longitudinally of said main frame, said main frame being provided with a transverse way, a slicing 70 unit adjustable on said way transversely of said main frame and adapted to be adjusted to operative position within said main frame or to an inoperative position at the side thereof, a table within said main frame, a feed conveyor on said 75

auxiliary frame adapted by the adjustment of said frame to be brought into position to deliver to said slicing unit, driving means for said conveyor including a variable speed unit, a second feed conveyor disposed at the rear of said table, a transfer conveyor comprising a carriage, jaws pivotally mounted on said carriage to engage an article on said table and transfer the same to said second feed conveyor, means for opening and closing said jaws at the ends of the stroke of the carriage, a control means for said jaw closing means including an article controlled trip operatively associated with said table, a control means for said first feed conveyor driving means disposed in advance of said variable speed unit thereof and operatively associated with said article controlled trip to be controlled thereby, a wrapping unit, a reciprocating plunger to which said second feed conveyor delivers delivering to said wrapping unit, a sealing unit to which the articles are delivered by said wrapping unit, said sealing unit comprising sealer elements acting to translate the articles through the sealing unit.

2. In a combined wrapping and slicing machine, the combination with a main frame, of an auxiliary frame mounted for adjustment longitudinally of said main frame said main frame being provided with a transverse way, a slicing unit adjustable on said way transversely of said main frame and adapted to be adjusted to operative position within said main frame or to an inoperative position at the side thereof, a table within said main frame, a feed conveyor on said auxiliary frame adapted by the adjustment of said frame to be brought into position to deliver to said table or to permit the adjustment of said slicing unit into operative position and into position to deliver to said slicing unit, driving means for said conveyor, a second feed conveyor disposed at the rear of said table, a transfer conveyor comprising a carriage, jaws pivotally mounted on said carriage to engage an article on said table and transfer the same to said second feed conveyor, means for opening and closing said jaws at the ends of the stroke of the carriage, a control means for said jaw closing means including an article controlled trip operatively associated with said table, a control means for said first feed conveyor driving means disposed in advance of said variable speed unit thereof and operatively associated with said article controlled trip to be controlled thereby, a wrapping unit, a reciprocating plunger to which said second feed conveyor delivers delivering to said wrapping unit, and a sealing unit to which the articles are delivered by said wrapping unit, said sealing unit comprising sealer elements acting to translate the articles through the sealing unit.

3. In a combined wrapping and slicing machine, the combination with a main frame, an auxiliary frame mounted for adjustment longitudinally of said main frame, said main frame being provided with a transverse way, a slicing unit adjustable on said way transversely of said main frame and adapted to be adjusted to operative position within said main frame or to an inoperative position at the side thereof, a table within said main frame, a feed conveyor on said auxiliary frame adapted by the adjustment of said frame to be brought into position to deliver to said table or to permit the adjustment of said slicing unit into operative position and into position to deliver to said slicing unit, driving means for said conveyor, a second feed conveyor disposed at the rear of said table, a transfer conveyor comprising a carriage, jaws pivotally mounted on said carriage to engage an article on said table and trans-

fer for the same to said second feed conveyor, means for opening and closing said jaws at the ends of the stroke of the carriage, a control means for said jaw closing means including an article controlled trip operatively associated with said table, a control means for said first feed conveyor driving means operatively associated with said article controlled trip to be controlled thereby, a wrapping unit, a reciprocating plunger to which said second feed conveyor delivers delivering to said wrapping unit, a sealing unit to which the articles are delivered by said wrapping unit, said sealing unit comprising sealer elements acting to translate the articles through the sealing unit, and a discharge conveyor to which said sealing unit delivers comprising a conveyor way and a plurality of driven feed belts at each side provided with individual belt tighteners, said wrapping and sealing units and said conveyor being disposed above said feed and transfer conveyors and above said slicing unit when it is in operative position relative to said feed and transfer conveyors.

4. In a combined wrapping and slicing machine, the combination with a main frame, of an auxiliary frame mounted for adjustment longitudinally of said main frame, said main frame being provided with a transverse way, a slicing unit adjustable on said way transversely of said main frame and adapted to be adjusted to operative position within said main frame or to an inoperative position at the side thereof, a table within said main frame, a feed conveyor on said auxiliary frame adapted by the adjustment of said frame to be brought into position to deliver to said table or to permit the adjustment of said slicing unit into operative position and into position to deliver to said slicing unit, driving means for said feed conveyor including a variable speed unit, a second feed conveyor comprising a carriage, jaws pivotally mounted on said carriage to engage an article on said table and transfer the same to said second feed conveyor, means for opening and closing said jaws at the ends of the stroke of the carriage, a control means for said jaw opening and closing means including an article controlled trip operatively associated with said table, and a control means for said first feed conveyor driving means disposed in advance of said variable speed unit thereof and operatively associated with said article controlled trip to be controlled thereby.

5. In a combined wrapping and slicing machine, the combination with a main frame, of an auxiliary frame mounted for adjustment longitudinally of said main frame, said main frame being provided with a transverse way, a slicing unit adjustable on said way transversely of said main frame and adapted to be adjusted to operative position within said main frame or to an inoperative position at the side thereof, a table within said main frame, a feed conveyor on said auxiliary frame adapted by the adjustment of said frame to be brought into position to deliver to said table or to permit the adjustment of said slicing unit into operative position and into position to deliver to said slicing unit, driving means for said feed conveyor, a second feed conveyor disposed at the rear of said table, a transfer conveyor comprising a carriage, jaws pivotally mounted on said carriage to engage an article on said table and transfer the same to said second feed conveyor, means for opening and closing said jaws at the ends of the stroke of the carriage, a control means for said jaw opening and closing means including an article controlled trip operatively associated with

said table, and a control means for said first feed conveyor driving means operatively associated with said article controlled trip to be controlled thereby.

- 5 6. In a combined wrapping and slicing machine, the combination with a main frame, of an auxiliary frame mounted for adjustment longitudinally of said main frame, said main frame being provided with a transverse way, a slicing unit adjustable on said way transversely of said main frame and adapted to be adjusted to operative position within said main frame or to an inoperative position at the side thereof, a table within said main frame, a feed conveyor on said auxiliary frame adapted by the adjustment of said frame to be brought into position to deliver to said table or to permit the adjustment of said slicing unit into operative position and into position to deliver to said slicing unit, a screw adjusting means for said auxiliary frame, means for driving said feed conveyor, a second feed conveyor comprising a carriage, jaws pivotally mounted on said carriage to engage an article on said table and transfer the same to said second feed conveyor, means for opening and closing said jaws at the ends of the stroke of the carriage, a control means for said jaw opening and closing means including an article controlled trip operatively associated with said table, and a control means for said first feed conveyor driving means operatively associated with said article controlled trip to be controlled thereby.
7. In a combined wrapping and slicing machine, the combination with a main frame, of an auxiliary frame mounted for adjustment longitudinally of said main frame, said main frame being provided with a transverse way, a slicing unit adjustable on said way transversely of said main frame and adapted to be adjusted to operative position within said main frame or to an inoperative position at the side thereof, a table on said main frame, a feed conveyor on said auxiliary frame adapted by the adjustment of said frame to be brought into position to deliver to said table or to permit the adjustment of said slicing unit into operative position and into position to deliver to said slicing unit, driving means for said conveyor including a variable speed unit, a wrapping unit, means for translating articles to be wrapped from said table to said wrapping unit, a control means for said translating means including an article actuated trip operatively associated with said table, a control means for said feed conveyor driving means disposed in advance of said variable speed unit of said variable speed unit thereof and operatively associated with said article actuated trip.
8. In a combined wrapping and slicing machine, the combination with a main frame, of an auxiliary frame mounted for adjustment longitudinally of said main frame, said main frame being provided with a transverse way, a slicing unit adjustable on said way transversely of said main frame and adapted to be adjusted to operative position within said main frame or to an inoperative position at the side thereof, a table on said main frame, a feed conveyor on said auxiliary frame adapted by the adjustment of
- 5 9. In a combined wrapping and slicing machine, the combination with a main frame, of an auxiliary frame mounted for adjustment longitudinally of said main frame, said main frame being provided with a transverse way, a slicing unit adjustable on said way transversely of said main frame and adapted to be adjusted to operative position within said main frame or to an inoperative position at the side thereof, a table on said main frame, a feed conveyor on said auxiliary frame adapted by the adjustment of said frame to be brought into position to deliver to said table or to permit the adjustment of said slicing unit into operative position and into position to deliver to said slicing unit, driving means for said conveyor including a variable speed unit, a wrapping unit, means for translating articles to be wrapped from said table to said wrapping unit, said means acting to support the articles at the ends thereof throughout the translating movement, a control means for said translating means including an article actuated trip operatively associated with said table, and a control means for said feed conveyor driving means disposed in advance of said variable speed unit thereof and operatively associated with said article actuated trip.
10. In a combined wrapping and slicing machine, the combination with a main frame, of an auxiliary frame mounted for adjustment longitudinally of said main frame, said main frame being provided with a transverse way, a slicing unit adjustable on said way transversely of said main frame and adapted to be adjusted to operative position within said main frame or to an inoperative position at the side thereof, a feed conveyor on said auxiliary frame adapted by the adjustment of said frame to be brought into position to deliver to said table or to permit the adjustment of said slicing unit into operative position and into position to deliver to said slicing unit, a wrapping unit, means for translating articles to be wrapped from said table to said wrapping unit, a sealing unit to which the articles are delivered by said wrapping unit, said sealing unit comprising sealing elements adapted to translate the articles through the sealing unit, and a discharge conveyor to which said sealing unit delivers comprising a conveyor way and a plurality of driven feed belts provided with individual belt tighteners.
11. In a combined wrapping and slicing machine, the combination with a main frame, of an auxiliary frame mounted for adjustment longitudinally of said main frame, said main frame being provided with a transverse way, a slicing unit adjustable on said way transversely of said main frame and adapted to be adjusted to operative position within said main frame or to an inoperative position at the side thereof, a feed conveyor on said auxiliary frame adapted by the adjustment of

adjustment of said frame to be brought into position to deliver to said table or to permit the adjustment of said slicing unit into operative position and into position to deliver to said slicing unit, a wrapping unit, and means for translating articles to be wrapped from said table to said wrapping unit.

12. In a combined wrapping and slicing machine, the combination with a main frame, of 10 an auxiliary frame mounted for adjustment longitudinally of said main frame, said main frame being provided with a transverse way, a slicing unit adjustable on said way transversely of said main frame and adapted to be adjusted to operative position within said main frame or to an 15 inoperative position at the side thereof, a feed conveyor on said auxiliary frame adapted by the adjustment of said frame to be brought into position to deliver to said table or to permit the adjustment of said slicing unit into operative position and into position to deliver to said slicing unit, a screw adjusting means for said auxiliary frame, a wrapping unit, and means for translating articles to be wrapped from said table to said 20 wrapping unit.

13. In a combined wrapping and slicing machine, the combination with a main frame provided with article conveying means, of a slicing unit adapted to be adjusted into and out of operative relation to said article conveying means, a 30 longitudinally adjustable feed conveyor adapted to be adjusted into operative relation to said article conveying means on said main frame or into position to permit the adjustment of said 35 slicing unit into operative relation thereto and to deliver to said slicing unit, and wrapping and sealing means to which said conveying means on said main frame delivers disposed above such conveying means and said slicing unit when in 40 its operative position.

14. In a combined wrapping and slicing machine, the combination with a main frame provided with article conveying means, of a slicing unit adapted to be adjusted into and out of operative relation to said article conveying means, and a longitudinally adjustable feed conveyor 45 adapted to be adjusted into operative relation to said article conveying means on said main frame or into position to permit the adjustment of said 50 slicing unit into operative relation thereto and to deliver to said slicing unit.

15. In a combined wrapping and slicing machine, the combination of wrapping means, sealing means to which the wrapping means delivers, 55 a conveying means delivering to said wrapping means, a slicing unit adjustable into and out of operative relation to said conveying means, and a feed conveyor adjustable to deliver to said slicing unit when it is in operative relation or to 60 said conveying means when the slicing unit is in inoperative position.

16. In a combined wrapping and slicing machine, the combination of wrapping means, a conveying means delivering to said wrapping means, a slicing unit adjustable into and out of operative relation to said conveying means, and a feed conveyor adjustable to deliver to said slicing unit when it is in operative relation or to 65 said conveying means when the slicing unit is in inoperative position.

17. A combined wrapping and slicing machine comprising a wrapping means, a conveying means operatively associated therewith, a slicing unit adjustable into and out of operative relation to such conveying means, and a feed means adjust-

able to deliver to said conveying means or to said slicing unit.

18. The combination with a slicing machine, of a table to which the slicing machine delivers, a reciprocating transfer means acting to engage 5 the ends of the loaves on said table, a feed conveyor for said slicing machine, a driving means for said feed conveyor including a variable speed unit, and control means for said conveyor drive means actuated by the articles at the rear of the 10 slicing machine.

19. The combination with a slicing machine, of a table to which the slicing machine delivers, a reciprocating transfer means acting to engage 15 the ends of the loaves on said table, a feed conveyor for said slicing machine, a driving means for said feed conveyor, and control means for said conveyor drive means actuated by the articles at the rear of the 20 slicing machine.

20. In an apparatus of the class described, the 25 combination with a feed conveyor, driving means therefor including a variable speed unit, a table to which said feed conveyor delivers, and a control means for said feed conveyor disposed in advance of said variable speed unit, said control 25 means including a trip operatively associated with said table to be actuated by the articles translated across the table.

21. In a machine of the class described, the 30 combination of a table, a reciprocating carriage, article engaging jaws on said carriage, means for closing the jaws at the rear end of the stroke of the carriage and for opening them at the forward end of its stroke, the means for closing the jaws being controlled by the delivery of an article upon 35 said table, a feed means operatively associated with said table, and control means for said feed means operatively associated with the table to be controlled by an article thereon.

22. In a machine of the class described the 40 combination with wrapping means including a reciprocating carriage, of a conveyor way to which said wrapping means delivers, said wrapping means including end flap folders operative 45 as the article is translated along said way, end sealers to which the articles are delivered from said end flap folders operatively associated with said way and comprising sets of bar-like sealer members arranged in parallel relation with each 50 other and with the way, the sealer members of the sets being arranged in alternating relation, eccentrics on which said sets of sealer members are mounted disposed in opposed relation so that the sets of sealer members are alternately projected 55 to article engaging position and retracted and so that the sealer members travel in orbital paths and are in projected article engaging position on their forward stroke, a series of upwardly curved bottom sealer members, said way having a transverse opening through which said bottom sealer members may engage an article, a support on which said bottom sealer members are pivotally mounted, springs yieldingly supporting said bottom sealer members on their pivots, means for 60 slidably supporting the rear end of said bottom sealer member support, an eccentric for supporting the front end of said bottom sealer member support whereby an orbital movement is imparted to said bottom sealer members and they are 65 moved forwardly on the article engaging stroke thereof, pressure bars disposed longitudinally of said way above said bottom sealer members, pivotally mounted supporting arms on which said 70 pressure bars are pivotally mounted, and screws 75

having threaded engagement with said arms and constituting adjustable rests therefor.

23. In a machine of the class described, the combination with wrapping means including a reciprocating carriage, of a conveyor way to which said wrapping means delivers, said wrapping means including end flap folders operative as the article is translated along said way, end sealers to which the articles are delivered from said end flap folders operatively associated with said way and comprising sets of bar-like sealer members arranged in parallel relation with each other and with the way, the sealer members of the sets being arranged in alternating relation, eccentric on which said sets of sealer members are alternately projected to article engaging position and retracted and so that the sealer members travel in orbital paths and are in projected article engaging position on their forward stroke, a series of upwardly curved bottom sealer members, said way having a transverse opening through which said bottom sealer members may engage an article, a support on which said bottom sealer members are pivotally mounted, springs yieldingly supporting said bottom sealer members on their pivots, means for slidably supporting the rear end of said bottom sealer member support, and an eccentric for supporting the front end of said bottom sealer member support whereby an orbital movement is imparted to said bottom sealer members and they are moved forwardly on the article engaging stroke thereof.

24. In a machine of the class described, the combination with wrapping means including a reciprocating carriage, of a conveyor way to which said wrapping means delivers, said wrapping means including end flap folders operative as the article is translated along said way, end sealers to which the articles are delivered from said end flap folders operatively associated with said way and comprising sets of bar-like sealer members arranged in parallel relation with each other and with the way, the sealer members of the sets being arranged in alternating relation, and eccentric on which said sets of sealer members are mounted disposed in opposed relation so that the sets of sealer members are alternately projected to article engaging position and retracted and so that the sealer members travel in orbital paths and are in projected article engaging position on their forward stroke.

25. In a machine of the class described, the combination with a conveyor way, end sealers operatively associated with said way and comprising sets of bar-like sealer members arranged in parallel relation with each other and with the way, the sealer members of the sets being arranged in alternating relation, eccentric on which said sets of sealer members are mounted disposed in opposed relation so that the sets of sealer members are alternately projected to article engaging position and retracted and so that the sealer members travel in orbital paths and are in projected article engaging position on their forward stroke, a series of upwardly curved bottom sealer members, said way having a transverse opening through which said bottom sealer members may engage an article, a support on which said bottom sealer members are pivotally mounted, springs yieldingly supporting said bottom sealer members on their pivots, means for slidably supporting the rear end of said bottom sealer member support, an eccentric for supporting the front end of said bottom sealer member support whereby an orbital movement is im-

parted to said bottom sealer members and they are moved forwardly on the article engaging stroke thereof, and pivotally and adjustably mounted pressure bars above said bottom sealer members.

26. In a machine of the class described, the combination with a conveyor way, end sealers operatively associated with said way and comprising sets of bar-like sealer members arranged in parallel relation with each other and with the way, the sealer members of the sets being arranged in alternating relation, eccentric on which said sets of sealer members are mounted disposed in opposed relation so that the sets of sealer members are alternately projected to article engaging position and retracted and so that the sealer members travel in orbital paths and are in projected article engaging position on their forward stroke, a series of upwardly curved bottom sealer members, said way having a transverse opening through which said bottom sealer members may engage an article, a support on which said bottom sealer members are pivotally mounted, springs yieldingly supporting said bottom sealer members on their pivots, means for slidably supporting the rear end of said bottom sealer member support, and an eccentric for supporting the front end of said bottom sealer member support whereby an orbital movement is imparted to said bottom sealer members and they are moved forwardly on the article engaging stroke thereof.

27. In a machine of the class described, the combination with a conveyor way, end sealers operatively associated with said way and comprising sets of bar-like sealer members arranged in parallel relation with each other and with the way, the sealer members of the sets being arranged in alternating relation, and eccentric on which said sets of sealer members are mounted disposed in opposed relation so that the sets of sealer members are alternately projected to article engaging position and retracted and so that the sealer members travel in orbital paths and are in projected article engaging position on their forward stroke.

28. In a machine of the class described, the combination of a way, sealers operatively associated with said way and comprising elongated heated sealer elements disposed in parallel relation and adapted to coact with the ends of an article on the way, and eccentric on which said sealer elements are mounted disposed in opposed relation so that the sealer elements are alternately projected to article engaging position and retracted and so that the sealer elements travel in orbital paths and are in projected article engaging position on their forward strokes, said sealer elements constituting feed means for advancing the article to be sealed along said way.

29. In a machine of the class described, the combination with a conveyor way, of a series of upwardly curved bottom sealer members, said way having a transverse opening through which said bottom sealer members may engage an article, a support on which said bottom sealer members are pivotally mounted, springs yieldingly supporting said bottom sealer members on their pivots, means for slidably supporting the rear end of said bottom sealer member support, an eccentric for supporting the front end of said bottom sealer member support whereby an orbital movement is imparted to said bottom sealer members and they are moved forwardly on the article engaging stroke thereof, pressure bars disposed longitudi-

- dinarily of said way above said bottom sealer members, pivotally mounted supporting arms on which said pressure bars are pivotally mounted, and screws having threaded engagement with said 5 arms and constituting adjustable rests therefor.

30. In a machine of the class described, the combination with a conveyor way, of a series of upwardly curved bottom sealer members, said way having a transverse opening through which 10 said bottom sealer members may engage an article, a support on which said bottom sealer members are pivotally mounted, springs yieldingly supporting said bottom sealer members on their pivots, means for slidably supporting the rear end 15 of said bottom sealer member support, and an eccentric for supporting the front end of said bottom sealer member support whereby an orbital movement is imparted to said bottom sealer members and they are moved forwardly on the article 20 engaging stroke thereof.

31. In a machine of the class described, the combination of a way, a heated sealer element operatively associated with said way, and eccentrics on which said sealer element is mounted driven 25 so that the sealer element travels in an orbital path and is in the projected article engaging position on its forward stroke, said sealer element constituting a feed means for advancing the article 30 to be sealed along said way.

32. In a machine of the class described, the combination with a conveyor way, of heated sealer elements operatively associated with the way, and crank means acting to drive said elements in an orbital path with the elements parallel 35 at all times to the way and so that they are in article engaging position only on their forward strokes whereby they act as step feed means for the article to be sealed.

33. The combination with a conveyor way, of driven heated sealing elements, and crank means acting to drive said elements in an orbital path with the elements parallel at all times to the way and so that an article is advanced in steps 40 along the way by the engagement of the sealing elements therewith.

34. In a machine of the class described, the combination with a conveyor way, of a heated sealer element operatively associated with the way, and crank means acting to drive said element in an orbital path with the element parallel 45 at all times to the way and so that it is in article engaging position only on its forward stroke whereby it acts as step feed means for the article to be sealed.

35. The combination with a conveyor way, of driven sealing elements engaging the article to be sealed and advancing it along the way, and heating elements movable with and in constant contact with said sealing elements.

36. In a machine of the class described, the combination with a conveyor way, of driven sealer elements operatively associated with the way and acting to feed the article to be sealed 55 along the way, and heating elements fixed to said sealer elements for movement therewith.

37. In a machine of the class described, the combination of a way, a series of upwardly curved independently movable bottom sealer elements, said way having an opening so that the 60 said bottom sealer elements may contact an article to be sealed, means yieldingly urging said bottom sealer members to article engaging position, and means for actuating said sealer elements in an orbital path and so that they are

65 moved forwardly on the article engaging stroke thereof.

38. In a machine of the class described, the combination of a way, a series of independently movable bottom sealer elements, said way having an opening so that the said bottom sealer elements may contact an article to be sealed, and means for actuating said sealer elements in an orbital path and so that they are moved forwardly on the article engaging stroke thereof.

39. In a machine of the class described, the combination with a wrapping unit, a plunger for delivering articles to be wrapped to said wrapping unit, a wrapper feed means comprising an endless paper feed conveyor, a pressure roller 15 operatively associated therewith, means for adjusting said pressure roller longitudinally of said conveyor, a wrapper supporting table mounted to reciprocate across the path of said plunger and adapted to support the forward portion of the wrapper delivered from said wrapper conveyor, an adjustable stop operatively associated with said wrapper supporting table, an article conveyor adapted to deliver to said plunger, means for operating said wrapper supporting 20 table in synchronized relation to said plunger, driving means for said wrapper delivery conveyor including a driving clutch, and means for controlling said clutch including a trip operatively associated with said article conveyor to be actuated by the articles delivered to the plungers thereby.

40. In a machine of the class described, the combination with a wrapping unit, a plunger for delivering articles to be wrapped to said wrapping unit, a wrapper feed means comprising an endless paper feed conveyor, a pressure roller 25 operatively associated therewith, means for adjusting said pressure roller longitudinally of said conveyor, a wrapper supporting table mounted to reciprocate across the path of said plunger and adapted to support the forward portion of the wrapper delivered from said wrapper conveyor, an adjustable stop operatively associated with said wrapper supporting table, and means 30 for operating said wrapper supporting table thereby.

41. In a machine of the class described, the combination with a wrapping unit, a plunger for delivering articles to be wrapped to said wrapping unit, a wrapper feed means comprising an endless paper feed conveyor, a wrapper supporting table mounted to reciprocate across the path of said plunger and adapted to support the forward portion of the wrapper delivered from said wrapper conveyor, an article conveyor adapted to deliver to said plunger, means for operating said wrapper supporting table in synchronized relation to said plunger.

42. In a machine of the class described, the combination with a wrapping means, a plunger for delivering articles to be wrapped to said wrapping means, a wrapper feed means, a wrapper supporting table mounted to reciprocate across the path of said plunger and adapted to support the forward portion of the wrapper delivered from said wrapper conveyor, an article conveyor adapted to deliver to said plunger, means for operating said wrapper supporting table in synchronized relation to said plunger, driving 65 means for said wrapper delivery conveyor including a driving clutch, and means for controlling said clutch including a trip operatively associated with said article conveyor to be actuated by the articles delivered to the plungers thereby.

43. In a machine of the class described, the combination with a wrapping means, a plunger for delivering articles to be wrapped to said wrapping means, a wrapper feed means, a wrapper supporting table mounted to reciprocate across the path of said plunger and adapted to support the forward portion of the wrapper delivered from said wrapper conveyor, an article conveyor adapted to deliver to said plunger, means for operating said wrapper supporting table in synchronized relation to said plunger, driving 70 means for said wrapper delivery conveyor including a driving clutch, and means for controlling said clutch including a trip operatively associated with said article conveyor to be actuated by the articles delivered to the plungers thereby.

means for said wrapper feed means including a driving clutch, and means for controlling said clutch including a trip operatively associated with said article conveyor to be actuated by the articles delivered to the plungers thereby.

43. In a machine of the class described, the combination with a wrapping means, a plunger for delivering articles to be wrapped to said wrapping means, a wrapper feed means, a wrapper supporting table mounted to reciprocate across the path of said plunger and adapted to support the forward portion of the wrapper delivered from said wrapper conveyor, an article conveyor adapted to deliver to said plunger, and means for operating said wrapper supporting table in synchronized relation to said plunger.

44. In a wrapping machine the combination with a wrapping mechanism including coacting grippers and a reciprocatingly mounted plate-like bottom folder, a feed plunger adapted to deliver the articles to be wrapped to said grippers with the wrapper draped over the article, the bottom folder constituting a draping member, paper feed means for delivering and positioning wrappers across the path of the articles delivered by said plunger including a wrapper delivery conveyor, a pressure roller operatively associated with said delivery conveyor and adjustable longitudinally thereof to limit the feeding of the wrapper by the conveyor, a table operatively associated with the paper delivery conveyor to receive and support the wrapper delivered thereby, said table being mounted to reciprocate across the path of the plunger, an adjustable paper stop operatively associated with said table, means for reciprocating said plunger and paper supporting table in timed relation, driving means for said wrapper delivery conveyor, and means for actuating the bottom folder in timed relation to the actuation of said plunger so that the plunger has a tensioning engagement with the wrapper as it is folded beneath the article by said bottom folder, the plunger and bottom folder engaging and supporting the wrapper substantially throughout the width thereof.

45. In a wrapping machine, the combination with a wrapping mechanism including coacting grippers and a reciprocatingly mounted plate-like bottom folder, a feed plunger adapted to deliver the articles to be wrapped to said grippers with the wrapper draped over the article, the bottom folder constituting a draping member, paper feed means for delivering and positioning wrappers across the path of the articles delivered by said plunger, a table operatively associated with the paper delivery conveyor to receive and support the wrapper delivered thereby, said table being mounted to reciprocate across the path of the plunger, means for reciprocating said plunger and paper supporting table in timed relation, driving means for said wrapper delivery conveyor, and means for actuating the bottom folder in timed relation to the actuation of said plunger so that the plunger has a tensioning engagement with the wrapper as it is folded beneath the article by said bottom folder, the plunger and bottom folder engaging and supporting the wrapper substantially throughout the width thereof.

46. In a wrapping machine, the combination with a wrapping mechanism including coacting grippers and a reciprocatingly mounted plate-like bottom folder, a feed plunger adapted to deliver the articles to be wrapped to said grippers with the wrapper draped over the article, the bottom folder constituting a draping member,

paper feed means for delivering and positioning wrappers across the path of the articles delivered by said plunger, a table operatively associated with the paper delivery conveyor to receive and support the wrapper delivered thereby, said table being mounted to reciprocate across the path of the plunger, driving means for said wrapper delivery conveyor including a clutch, control means for said clutch including an article controlled trip, and means for actuating the bottom folder in timed relation to the actuation of said plunger so that the plunger has a tensioning engagement with the wrapper as it is folded beneath the article by said bottom folder, the plunger and bottom folder engaging and supporting the wrapper substantially throughout the width thereof.

47. In a wrapping machine, the combination with a wrapping mechanism including a reciprocatingly mounted plate-like bottom folder, a feed plunger adapted to deliver the articles to be wrapped to said wrapping mechanism with the wrapper draped over the article, the bottom folder constituting a draping member, paper feed means for delivering and positioning wrappers across the path of the articles delivered by said plunger, a table operatively associated with the paper delivery conveyor to receive and support the wrapper delivered thereby, said table being mounted to reciprocate across the path of the plunger, means for reciprocating said plunger and paper supporting table in timed relation, and means for actuating the bottom folder in timed relation to the actuation of said plunger so that the plunger has a tensioning engagement with the wrapper as it is folded beneath the article by said bottom folder, the plunger and bottom folder engaging and supporting the wrapper substantially throughout the width thereof.

48. In a machine of the class described, the combination with a wrapping means, means for feeding articles to be wrapped thereto including a conveyor, a paper feed means including feed rollers, one of which is hollow and provided with cooling fluid connections, a paper cutter disposed at the rear of said feed rollers, wrapper delivery belts disposed at the rear of said cutter, a pressure roller operatively associated with said belts and supported for adjustment longitudinally thereof, driving means for said feed rollers, cutter and wrapper delivery belts including a clutch, and a control means for said clutch including a trip operatively associated with said article conveyor to be actuated by the articles translated by said conveyor.

49. In a machine of the class described, the combination with a wrapping means, means for feeding articles to be wrapped thereto including a conveyor, a paper feed means, a paper cutter disposed at the rear of said feed means, wrapper delivery belts disposed at the rear of said cutter, a pressure roller operatively associated with said belts, means including crank arms supporting said pressure roller for adjustment longitudinally of said belts, driving means for said feed means, cutter and wrapper delivery belts including a clutch, and a control means for said clutch including a trip operatively associated with said article conveyor to be actuated by the articles translated by said conveyor.

50. In a machine of the class described, the combination with a wrapping means, means for feeding articles to be wrapped thereto, a wrapper feed means including feed rollers, one of which is hollow and provided with cooling fluid

connections, a paper cutter disposed at the rear of said feed rollers, a wrapper delivery conveyor disposed at the rear of said cutter, driving means for said feed rollers, cutter and wrapper delivery conveyor including a clutch, and a control means for said clutch including a trip operatively associated with said article conveyor to be actuated by the articles translated by said conveyor.

51. In a machine of the class described, the combination with a wrapping means, means for feeding articles to be wrapped thereto, a wrapper feed means having wax hardening means associated therewith, a paper cutter disposed at the rear of said feed means, a wrapper delivery conveyor disposed at the rear of said cutter, driving means for said feed means, cutter and wrapper delivery conveyor including a clutch, and control means for said clutch including a trip operatively associated with said article conveyor to be actuated by the articles translated by said conveyor.

52. In a machine of the class described, the combination with a wrapping unit, feeds for feeding articles to be wrapped thereto, a wrapper feed means including feed rollers, one of which is hollow and provided with cooling fluid connections, a paper cutter disposed at the rear of said feed rollers, and a wrapper delivery conveyor disposed at the rear of said cutter.

53. In a structure of the class described, the combination with a way, of a plurality of shafts disposed in vertical parallel relation, a plurality of circular disk-like sealer elements arranged in spaced relation on each shaft, the sealer elements of adjacent shafts being disposed in staggered interlapping relation, and means for driving the shafts in the same direction whereby the sealer elements cooperate to translate the article to be sealed along the sealer way.

54. In a structure of the class described, the combination of a plurality of shafts disposed in parallel relation, a plurality of circular disk-like sealer elements arranged in spaced relation on each shaft, the sealer elements of adjacent shafts being disposed in staggered interlapping relation, and means for driving the shafts in the same direction whereby the sealer elements cooperate to translate the article to be sealed.

55. In a structure of the class described, the combination of a plurality of shafts disposed in parallel relation, circular sealer elements on said shafts, and means for driving the shafts in the same direction whereby the sealer elements cooperate to translate the article to be sealed.

56. In a structure of the class described, the combination with a way, of a series of circular sealer elements, adjacent sealer elements being disposed in interlapping relation, and means for driving the sealer elements in the same direction whereby the sealer elements cooperate to translate the article to be sealed.

57. In a structure of the class described, the combination with a way, of a series of driven circular sealer elements, adjacent sealer elements being disposed in interlapping relation.

65 58. In a structure of the class described, the combination with a way, of a series of circular sealer elements, and means for driving the sealer elements in the same direction whereby the sealer elements cooperate to translate the article to be sealed.

59. In a machine of the class described, the combination of a sealer way, sealer elements cooperating with the ends of the article and acting to translate the same along the way, and a delivery conveyor comprising vertically spaced belts cooperating with each end of the article and positioned to receive the article delivered by said sealer elements, said delivery conveyor belts being provided with independently adjustable belt tighteners whereby the gripping action of the individual belts upon the articles delivered may be independently adjusted to regulate their gripping engagement with an irregular article being translated.

60. In a machine of the class described, the combination of a sealer way, sealer elements cooperating with the ends of the article and acting to translate the same along the way, and a delivery conveyor comprising vertically spaced belts cooperating with each end of the article and positioned to receive the article delivered by said sealer elements, said delivery conveyor belts being independently adjustable whereby the gripping action of the individual belts upon the articles delivered may be independently adjusted to regulate their gripping engagement with an irregular article being translated.

61. In a machine of the class described, the combination with end sealing means, of a delivery conveyor comprising vertically spaced belts cooperating with each end of the article and positioned to receive the article delivered by said sealing means, said delivery conveyor belts being provided with independently adjustable belt tighteners whereby the gripping action of the individual belts upon the articles delivered may be independently adjusted to regulate their gripping engagement with an irregular article being translated.

62. In a machine of the class described, the combination with end sealing means, of a delivery conveyor comprising vertically spaced belts cooperating with each end of the article and positioned to receive the article delivered by said sealing means, said delivery conveyor belts being independently adjustable whereby the gripping action of the individual belts upon the articles may be independently adjusted to regulate their gripping engagement with an irregular article being translated.

63. In a machine of the class described, the combination of a way, a series of independently movable sealer elements operatively associated with said way, springs yieldingly urging said sealer members to article engaging position, and means for actuating said sealer elements in circular path with the elements parallel at all times to the way and so that they are moved forwardly on the article engaging stroke thereof.

64. In a machine of the class described, the combination of a way, a series of independently movable sealer elements operatively associated with said way, and means for actuating said sealer elements in circular path with the elements parallel at all times to the way and so that they are moved forwardly on the article engaging stroke thereof.
